[57] CLAIM

The ornamental design for a vehicular battery charger or similar article, substantially as shown and described.

DESCRIPTION

FIG. 1 is a top perspective view of a vehicular battery charger or similar article showing my new design;
FIG. 2 is a rear elevational view thereof, the front view being substantially identical;
FIG. 3 is a left side elevational view thereof, the right side being substantially identical; and
FIG. 4 is a bottom plan view thereof.

FIG. 1

FIG. 2

FIG. 3

FIG. 4
